NETHER GARMENT FOR BABIES

Norma M. Wurster, Hobart, Ind.

Application April 5, 1948, Serial No. 19,137

2 Claims. (Cl. 128—284)

1

This invention relates to undergarments for babies and an object of the invention is to provide a baby's undergarment comprising a body part such as a shirt or the like and a nether part removably secured to said body part and adapted to serve as a diaper.

Another object of the invention is to provide an undergarment of the character indicated above, the nether part of which is adapted to be secured to the body part and to be closed in protecting position without the use of safety or other pins.

A further object of the invention is to provide a baby's undergarment of the character indicated above, the nether part of which is adapted to be used independently of the body part.

A still further object of the invention is to provide a baby's undergarment of the character indicated above, the nether part of which is made from any suitable material arranged in two similar laminations and provided with a central pocket portion open on both ends and adapted to receive an absorbent inner panel.

Another object of the invention is to provide a garment of the character indicated above, adapted to be removed without disturbing the outer garments of the baby and without exposing the baby to sudden changes of temperature.

Other objects of the invention not specifically mentioned may appear in the following specification describing it with reference to the accompanying drawing illustrating a preferred embodiment of my invention. It is, however, to be understood that the invention is not to be limited or restricted to the exact construction and combination of parts described in the specification and shown in the drawing, but that such changes and modifications can be made which fall within the scope of the claims appended hereto.

In order that my invention may be better understood, I will now proceed to describe it with reference to the accompanying drawing, in the several figures of which similar parts are designated by similar reference characters and in which:

Figure 1 is an elevational front view of the baby's undergarment according to my invention;

Figure 2 is a sectional view taken on the line 2—2 of Figure 1 and shown in a larger scale;

Figure 3 is a sectional view taken on the line 3—3 of Figure 1;

Figure 4 is a view in plan of the nether part of the baby's undergarment as herein embodied with its corner portions turned back;

Figure 5 is a sectional view taken on the line 5—5 of Figure 4; and

2

Figure 6 is a view in top or end edge of the nether part.

The baby's undergarment herein embodied comprises a body part S which may be a shirt, a vest or the like made from any preferred suitable material. In the embodiment shown in the drawing it is provided with shoulder straps 10 adapted to extend from the back to the front over the shoulders of a baby and releasably secured to the front portion of the shirt by means of cooperating connecting means such as snaps 11, button and button holes or the like. The body part S of the garment extends downwardly approximately to the hips of the baby, and the top opening of said garment part is, after the shoulder straps 10 have been released from the front of the shirt, large enough to permit the removal of the body part S by pulling it down over the body of the baby without the necessity of removing or disturbing the outer garments of the baby. Attention is called to the fact that the shirt or body part S may be provided with sleeves and shoulder openings adapted to be closed by means of buttons and button holes or the like, instead of the shoulder straps 10 described above. Adjacent the lower edge of the body part S one part 12 of a pair of cooperating connecting means such as snaps, buttons and button holes is arranged on said garment part at the right and left side of the garment front.

The lower or nether garment part D as herein embodied comprises two overlying laminations 13 and 14 of any desired suitable material herein described as having their longitudinal margins connected but their end margins free. The overlying laminations 13 and 14 result from the weaving of an initially tubular body, which has been flattened. The overlying laminations 13 and 14 are herein shown as being substantially rectangular, it is however to be understood, that they may have any other suitable and desired outline. An inner pad or panel 15 of suitable absorbent material is inserted between the two overlying laminations and is arranged therein smoothly and is adapted to be removed therefrom easily and readily.

Adjacent each corner of the nether garment part D pleats 16 are arranged extending from the transverse edges of the nether garment part longitudinally with respect to said part. Adjacent one of the transverse edges of the nether garment part D a connecting means 17 adapted to cooperate with the member 12 on the body part S is arranged adjacent the longitudinal edge of the nether garment part. Inwardly of each of these connecting means 17 and closely adjacent

thereto a plurality of connecting means 18 similar to the member 12 is arranged on the nether garment part D. Adjacent the other transverse edge of the nether garment part a plurality of connecting members 19 similar to the member 17 is secured to the nether garment portion D adjacent each longitudinal edge thereof.

When the body part S of the garment has been put on the body and is secured in position by means of the shoulder straps 10 and the securing means 11, the nether garment part D is attached thereto by engaging the connecting members 12 on said body garment part by the cooperating connecting members 17 on the nether garment part D, so that the latter hangs down from the body garment part in front of the baby. Then the nether garment part D is folded upwardly between the legs of the baby and the corner portions of the portion of the nether garment part now arranged in the back of the baby are folded over the corner portions of said garment part secured to the body garment part. The connecting members 18 on these corner portions are engaged by the connecting members 19 on the folded over portions of the nether garment portion, which is thereby securely arranged in protective position.

In Figures 4 and 5 the nether garment part D is illustrated in detail. It comprises, as described above, the overlying two laminations 13 and 14 and the absorbent central panel 15 or padding.

It is to be further and particularly pointed out, that pleats 16 can be let out as needed for size adjustment. In the embodiment of the invention as illustrated in the accompanying drawing 35 the pleats 16 at each corner of the nether garment part D are shown in pairs. Obviously this number can be varied as preferred.

It is also to be pointed out that the body garment part or shirt S, when the straps 10 are unfastened, has a top opening of a size to permit removal of the same when wet or soiled without disturbance to any outer clothing. This is of particular advantage as it saves undressing the child when the part or shirt S needs to be removed.

I claim:

1. In a nether garment for infants, a body formed of two elongated panels secured together

along the longitudinal side edges thereof, an absorbent pad housed between said panels and removable therefrom through either of the unsecured transverse ends of the body for replacement, said body being foldable at its transverse center for application to the infant and having several closely spaced and longitudinally extending pleats formed in its transverse end edge portions adjacent the corners thereof to allow the snug fit of said edge portions about the waist of the infant, and separable fastenings carried at the corners of the body which are foldable one over the other for the engagement of the complementary parts of said fastening with each other to secure the garment in place.

2. The garment as defined in claim 1, with the said body of elongated tubular form and flattened to provide double front and back panels, said panels being secured together inwardly from and 10 parallel to the longitudinal lines of fold of the body, and said absorbent pad is housed between the panels and between the lines of securement of the same to each other, said pleats being formed outwardly from the said lines of securement of the panels.

NORMA M. WURSTER.
